UNITED STATES PATENT OFFICE.

WILLIAM J. STENGER, OF MOHALL, NORTH DAKOTA.

COUPLING FOR TRACTION-ENGINES.

No. 911,456.

Specification of Letters Patent.

Patented Feb. 2, 1909.

Application filed July 17, 1908. Serial No. 444,079.

To all whom it may concern:

Be it known that I, WILLIAM J. STENGER, a citizen of the United States, residing at Mohall, in the county of Ward and State of 5 North Dakota, have invented a new and useful Coupler for Traction-Engines, of which the following is a specification.

This invention relates generally to couplers and specifically to devices of the above- 10 mentioned class which are peculiarly adapted for use upon traction engines.

The objects of the invention are, the provision in a merchantable form, of a device of the above-mentioned class which shall be 15 inexpensive to manufacture, facile in operation and devoid of complicated parts; the provision of detent and releasing mechanisms of a novel form; and finally, the positioning of the component parts to form a 20 compact and presentable coupler.

With these objects in view, together with others which a perusal of this specification will reveal to those skilled in the art, the invention consists in the novel construction 25 and arrangement of parts hereinafter described, delineated in the accompanying drawings and particularly pointed out in the appended claims, it being understood that various changes in the form, proportions, size and minor details of the structure 30 may be made without departing from the spirit or sacrificing any of the advantages of the invention.

Similar numerals of reference are employed to indicate corresponding parts throughout the several figures of the drawings.

In the accompanying drawings; Figure 1 is a top plan of my invention set to receive 40 a conventional coupling pin 19; Fig. 2 is a top plan upon an enlarged scale, the cover 2 being removed and the coupling mechanism shown in an open position; Fig. 3 is a side elevation upon a reduced scale; Fig. 4 is a top plan upon the same scale as Fig. 2, the cover 2 being removed and the coupling mechanism shown in a closed position.

In carrying out my invention, I provide a 45 housing 1, comprising preferably a cover 2 and a base-plate 3. The housing 1 is provided with an interior chamber, open at its sides and terminated at its rear by a partition 4. The forward end of the chamber is terminated by a straight vertical face 5, disposed at an acute angle to the draft-line 55 X—X, the said straight vertical face 5 be-

ing formed by the rear ends of the head-blocks 6 and 7, which, if desired, may be fashioned integral with the base-plate 3. The faces 5 form a shoulder, against which 60 bears with a sliding contact the detent 12.

The housing 1 is provided with a vertically incised pin-slot 8, flaring at its forward end to form the jaws 9 and 10. As the pin-slot 8 extends rearward beyond the 65 flaring portion, its walls proceed substantially parallel, to a point to the rear of the straight vertical face 5, the parallel walls being disposed at an angle to the draft line X—X, crossing the straight vertical face 70 5 substantially in the draft line X—X. The pin slot 8 terminates rearwardly in the portion 11, approximately parallel to the face 5.

Within the chamber is mounted the de- 75 tent 12, having its forward edge in sliding contact with the face 5. The detent 12 is provided with a vertically incised slot 13, extending rearward and laterally from the forward face of the detent 12, the lateral 80 inclination of the slot 13 being in a direction contrary to that assumed by the terminal 11 of the pin-slot. From one end of the rear edge of the detent 12, projects rearwardly the shoulder 14, adapted to engage successively the notches 15 and 16 in the lever 17, which is pivotally mounted at 18 within the housing 1, its movable end projecting without the housing 1. The slot 13 is so disposed in the detent 12 that, when the shoulder 14 90 engages the notch 16, the mouth of the slot 13 will register with the pin-slot 8, as shown in Fig. 2, and when the shoulder 14 engages the notch 15, the mouth of the slot 13 will have passed the pin-slot 8 closing the said 95 pin-slot, as shown in Fig. 4. When the de- tent 12 is in the position last above described, the terminal of the slot 13 will register with the end 11 of the pin-slot 8 to form a 100 socket within which the coupling pin 19 will be retained. The lever 17 is held in engagement with the detent 12 by the spring 20; retained at one end by the pintle 21 and fulcrumed upon the pintle 22. Conveniently 105 disposed bolts 23 may be provided to fasten the cover 2 to the base plate 3, the apertures in the base plate 3 adapted to receive the bolts 23, being designated by the numeral 24 in Figs. 2 and 4. My invention may be attached to the draw-bar 27 of the machine 110 of which it is a part, by any suitable method. I have shown, as adapted to this end, the

apertures 25, through which connecting bolts 26 may be passed.

To the movable end of the lever 17 may be attached means whereby the lever 17 may 5 be operated from the cab of the engine, or from any other point from which it is desired to control the device.

Let it be supposed that the detent 12 occupies the position shown in Figs. 1 and 2.

- 10 When the pin 19 moves between the jaws 9 and 10, it will be deflected into the slot 8, striking the detent 12 and sliding it into the position shown in Fig. 4 where it will be held by the engagement of the shoulder 14 with the notch 15, the slot 8, being closed as shown in Fig. 4. When it is desired to break the coupling, the lever 17 is moved rearward and the shoulder 14 freed from the notch 15. The pin 19 will follow the 20 portion 11 of the pin-slot, which said portion extends substantially parallel to the face 5. The pull upon the pin 19 in the direction of the draft-line X—X, will have a component in the line of the straight vertical face 5 and this component will cause the detent 12 to slide into the position shown in Figs. 1 and 2, freeing the pin 19 and permitting it to pass out between the jaws 9 and 10. Should the detent 12 assume the 25 position shown in Fig. 4 when the coupling pin 19 is not engaged by the detent 12, the detent 12 may be moved manually to the position shown in Figs. 1 and 2, when the device will be ready to receive and retain 30 the pin 19. When the detent 12 occupies the position shown in Figs. 1 and 2, the engagement of the shoulder 14 with the notch 16 will prevent the detent 12 from moving into an extreme and inoperative position.
- 35 40 Having thus described my invention, my claims are as follows:

1. A coupler comprising a housing having a vertically incised pin slot terminating in a lateral bend; head-blocks mounted in the 45 end of the housing upon opposite sides of the pin slot, the said head-blocks terminating rearwardly in straight vertical, alined faces disposed at an angle, laterally, to the draft line of the coupler; in sliding contact with the alined faces of the head-blocks, a detent having an excision from one of its edges, the said excision disposed laterally at an angle to the lateral bend of the pin slot, the mouth of the said excision being adapted to register 50 with the pin slot, and the terminal of the said excision being adapted to register with the lateral bend of the pin slot, alternately, in successive positions of the detent; means for limiting the movement of the detent.

2. In a device of the class described, a 60 housing having a vertically incised pin slot; head-blocks mounted in the housing upon opposite sides of the pin slot, the said head-blocks terminating rearwardly in straight, vertical, alined faces disposed at an angle, 65 laterally, to the draft line of the coupler; in sliding contact with the alined faces of the head-blocks, a detent adapted to intercept a portion of the pin slot; a shoulder projecting from the detent; mounted in the 70 housing, a lever having notches adapted to engage the shoulder in successive positions of the detent; means for holding the lever yieldingly against the detent.

3. In a device of the class described, a 75 housing having a vertically incised pin-slot terminating in a lateral bend; slidably mounted in the housing, a detent having an excision from one of its edges, the said excision disposed laterally at an angle to the 80 lateral bend of the pin-slot, the mouth of the said excision adapted to register with the pin-slot, and the terminal of the said excision adapted to register with the lateral bend of the pin-slot, alternately, in successive 85 positions of the detent; means for limiting the movement of the detent.

4. A coupler comprising a housing having a vertically incised pin-slot; head-blocks mounted in the end of the housing upon 90 opposite sides of the pin-slot, the said head-blocks terminating rearwardly in straight, vertical, alined faces disposed at an angle, horizontally, to the draft-line of the coupler; in sliding contact with the alined faces of the head-blocks, a detent adapted to intercept a portion of the pin-slot; means for limiting the movement of the detent.

5. In a coupler, a housing having a vertically incised pin-slot terminating in a lateral 100 bend; head-blocks mounted in the end of the housing upon opposite sides of the pin-slot, the said head-blocks terminating rearwardly in straight vertical alined faces disposed at an angle laterally to the draft line of the 105 coupler, and parallel to the terminal bend of the pin slot; in sliding contact with the alined faces of the head-blocks, a detent adapted to intercept the lateral bend of the pin slot; means for limiting the movement 110 of the detent.

In testimony that I claim the foregoing as my own, I have hereto affixed my signature in the presence of two witnesses.

WILLIAM J. STENGER.
